CLAIM

The ornamental design for a lost article locator, as shown and described.

DESCRIPTION

FIG. 1 is a front elevational view of the lost article locator of the present invention;

FIG. 2 is a rear elevational view of the lost article locator of FIG. 1, with a portion of the rear peeled away for clarity of illustration only;

FIG. 3 is a left side elevational view of the lost article locator of FIG. 1, the right side elevational view being a mirror image thereof;

FIG. 4 is a top plan view of the lost article locator of FIG. 1, the bottom plan view being a mirror image thereof; and, FIG. 5 is a reduced scale front elevational view of the lost article locator of FIG. 1 in use.

The broken lines showing of a remote control in FIG. 5 are for illustrative purposes only and form no part of the claimed design.
